OTHER PUBLICATIONS

Kason 1097 Door closer mounting instructions Nov. 7, 2016.

Primary Examiner — Ian Simmons*Assistant Examiner* — Yolanda Robinson(74) *Attorney, Agent, or Firm* — Baker Donelson; Dorian B. Kennedy(57) **CLAIM**

The ornamental design for a cold room door closer, as shown and described.

DESCRIPTION

FIG. 1 is a perspective view of a cold room door closer showing our new design.

FIG. 2 is a bottom view thereof.

FIG. 3 is a top view thereof.

FIG. 4 is a right side view thereof.

FIG. 5 is a left side view thereof.

FIG. 6 is a front view thereof; and,

FIG. 7 is a rear view thereof.

The broken lines depict portions of the cold room door closer that form no part of the claimed design.

1 Claim, 5 Drawing Sheets(56)
